Filed Aug. 5, 1955, Ser. No. 526,752

4 Claims. (Cl. 178—18)

This application is a continuation-in-part of our co-pending patent application Serial Number 496,306, filed March 23, 1955, entitled "Remote Writing Instrument" and has for its general object the provision of an improved fluid damping mechanism for a remote writing device of the general type there disclosed and claimed.

In the apparatus of the above-identified patent application the remote writing instrument uses electrical signals to indicate the position of the two writing arms of the transmitter. These signals may, for example, be the stator voltage generated in a pair of selsyn or synchro generators which vary in magnitude and phase in accord with the writing movements. In the receiver, cooperating motors, such as selsyn or synchro motors, are connected to respond to the same stator voltages. A follow-up or closed cycle control mechanism responds to the resultant induced rotor voltage in each selsyn or synchro to energize power drive means on the receiver to rotate the respective receiver arms in direction and amount to bring these arms to correspondence with the transmitted signals and hence with the positions of the transmitter arms.

Since the mechanism uses a follow-up system which is in essence a closed cycle control system, problems of hunting and instability are necessarily encountered. Moreover, these problems become more acute as the frictional and inertia resistance to writing arm movement increases and as increased amplification is embodied in the system. This hunting and instability problem is troublesome for a number of reasons. It may give rise to "flutter" or waving pen movement when a straight line is drawn, to the annoyance of the user. It may give rise to loss of writing response, especially at high speeds, so that readability is impaired and the chance of error increased. It may make the system critical as to external conditions of vibration, temperature, etc. For these and other reasons it is highly desirable to provide in the system itself a means to minimize hunting and instability.

In accordance with the present invention hunting and instability in the remote writing system is reduced or prevented by use of each writing arm drive motor itself as a mechanical damping device. This is accomplished by providing a silicone oil filling in each motor, so that the motor itself experiences resistance to rotor movement substantially proportional to the rapidity of movement. The damping effect thus provided is effective at a point in the follow-up system where it is most helpful in improving overall system operation and is in a form that does not entail reduced amplification, on the one hand, or additional mechanical or electrical damping apparatus, on the other. By a proper selection of the oil viscosity the damping constant can be controlled to provide a value capable of giving stable operation of the system without undesirable sluggish response.

In accordance with a further feature of the present invention this damping is effected with increased efficiency by providing a round rotor and stator motor construction. With this arrangement each motor defines

2

a very small annular gap within which the damping fluid is located and a highly efficient nearly perfect viscous resistance to rotor movement.

It is therefore a general object of the present invention to provide a receiver for a remote writing system characterized by a high degree of stability and lack of hunting and yet being of simple construction.

More specifically it is an object of the present invention to provide a receiver for a remote writing system wherein the writing arm drive motors themselves serve to introduce damping into the system.

Still another object of the present invention is to provide a receiver for a remote writing instrument wherein the receiver drive motors are mechanically arranged to provide effective damping.

Additionally, it is an object of the present invention to provide a receiver for a remote writing system which is characterized by simplicity, ruggedness, reliability, small size, and low cost, all achieved with a high degree of stability and lack of tendency to hunt or oscillate.

The novel features which we believe to be characteristic of our invention are set forth with particularity in the appended claims. Our invention itself, however, together with further objects and advantages thereof, will best be understood by reference to the following description taken in conjunction with the accompanying drawings in which:

Figure 1 is a diagrammatic view showing a complete remote writing mechanism of the kind to which the receiver of the present invention is applicable;

Figure 2 is a view in perspective of a receiver mechanism of the kind to which the present application is applicable;

Figure 3 is a schematic circuit diagram showing one complete channel of the remote writing system;

Figure 4 is a view in axial cross-section with the rotor in elevation of a receiver arm drive motor of the kind used in the system of the present invention;

Figure 5 is an enlarged cross-sectional view through axis 5—5, Figure 4; and

Figure 6 is a greatly enlarged fragmentary view of a portion of Figure 5 showing how the windings are embedded in the slots and the open faces of the slots are filled with insulating material to define smooth cylindrical inner and outer faces.

The complete remote writing system to which the present invention is applicable is described and claimed in our co-pending application entitled "Remote Writing Instrument," Serial Number 496,306, filed March 23, 1955 by the same applicants as the present invention and assigned to the same assignee. The complete construction of the system is described in that application in detail. For purposes of the present application it is sufficient to note that the system includes a transmitter 10, Figure 1, and a receiver 20. The transmitter includes a writing device 24 which is manually moved over a writing surface (not shown) to execute writing motions. The writing device is connected to the arms 32 and 28 of the transmitting selsyns or synchros 36 and 34, respectively, by the links 30 and 26. Arms 32 and 28 are pivotally connected to the links 30 and 26, respectively. Thus as writing proceeds the arms 32 and 28 swing in accordance with writing motions, the position of rotation of the arms 32 and 28 at any instant defining the position of the writing device 24.

In the receiver 20 a writing device 54, such as a ball point pen, is provided to trace the same writing movements as the writing device 24. The device 54 is linked by links 56 and 58 to the arms 60 and 62 which are rotated by the motors 64 and 66. As hereinafter described, these motors may conveniently be two-phase in-

duction motors each of which is driven in unison with the arms 32 and 28 of the transmitter 10. The resultant motion of arms 60 and 62 drives the pen 54 in the desired writing movements which constitute the same writing movements as those executed by the writing device 24.

A pair of selsyn or synchro receivers 170 and 70, Figure 1, are mechanically attached to the motors 64 and 66, respectively, to rotate in unison therewith. These receiving selsyns each are connected to the corresponding transmitter selsyn 36 or 34. Hence the electrical energization of the stator windings of the selsyns or synchros 170 and 70 produces a magnetic field in each which is oriented in accordance with the orientation of the rotors of the selsyns 36 and 34, respectively. The rotor windings of the selsyns 170 and 70 are connected to amplifiers 168 and 68, respectively, to supply power to the motors 64 and 66. This power is of magnitude and sense to drive the motors 64 and 66 in direction to bring the arms 60 and 62 to positions corresponding with those of arms 32 and 28 and thereby tend to reduce to zero the voltages induced in the rotors of selsyns 70 and 170.

The complete electrical circuit of one channel of the above described system is shown in Figure 3. In this figure, the rotor 34e of the selsyn 34 is mechanically rotated by the arm 28 (Figure 1) and receives alternating voltage from the source 72. The three stator windings of the selsyn 34 thereupon produce voltage across the terminals 34c in accord with the position of the rotor. This voltage is communicated through the conductors 34g to the stator winding terminals 70c of the similar stator winding on the receiving selsyn 70. The latter generates a magnetic field of orientation corresponding to the orientation of the rotor winding 34e of the transmitting selsyn 34. The rotor winding 70a of the receiving selsyn 70 has induced in it a voltage determined by the extent and direction its position of rotation departs from the position for no induced voltage at the particular current flows in the stator windings of that selsyn. This voltage is of the same frequency as source 72 (i.e. 60 cycles) and is amplified by amplifier 68 and applied to the quadrature winding 66c of the two-phase induction motor 66. The reference phase winding 66d of this motor is applied through the phase shifting capacitor 78 from source 72, which as above described furnishes the voltage for the rotor winding 34e of the transmitting selsyn 34. The resultant current flows in windings 66c and 66d create torque in the rotor 66b of the motor 66, torque determined by the magnitude and relative phase positions of the currents. The entire system is so constructed that this torque is in direction to restore the rotor 70a of the receiving selsyn 70 to the position of no-induced voltage.

It will thus be seen that the complete system of the receiver, including selsyn 70, amplifier 68 and motor 66, serves as a follow-up or closed cycle control system to bring the rotor of selsyn 70 to a position corresponding with that of the rotor of selsyn 34.

Figure 2 shows a perspective view of the receiving instrument of the kind to which the present invention is applicable. The drive motors 64 and 66 straddle the writing surface formed by the backing plate 50 and a serrated edge 50a across which the paper 44a may be torn. The paper is taken from the roll 44 supported by angle brackets 42 which are mounted on the base plate 40, the shaft 43 serving to hold the roll 44 in position. The pen 54 is pivotally connected to the links 56 and 58, each of which is pivotable at 57 and 59 in arms 60 and 62, respectively, to provide a mechanical linkage essentially like that of the transmitter. The arms 60 and 62 are mounted on the shafts 64a and 66a of the motors 64 and 66, respectively. The pen lifter bar 82 extends beneath the arms 56 and 58 and is operated by the arms 84 to lift the pen 54 in accordance with the writing movements of the transmitting pen. This is all as described in detail in the above-identified patent application.

Figures 4, 5 and 6 show in further detail the construc-

tion of the drive motor 66. As shown, the squirrel cage rotor 66b has a plurality of skewed peripheral slots 66k, each of which receives a conductor of aluminum or similar material. This is preferably accomplished by flowing molten aluminum into the assembled rotor laminations and then machining the rotor face to a smooth cylindrical configuration, all as is well understood in the induction motor art.

The stator 66e of the motor 66 has a plurality of sequentially shaped slots within which the windings 66c and 66d are disposed as shown. These windings are totally enclosed by the magnetic parts of the structure with the exception of the slots 66f located between each sequential slot and the inner periphery of the rotor. Each slot 66f is filled with a non-magnetic plastic material as is hereinbefore described.

In order to provide a maximum degree of magnetic efficiency, the air gap 66g, formed between the rotor 66b and the stator 66e, is made as short as possible. In practical motors of the kind used in the apparatus of the present invention the diameter of the rotor 66a might be about $\frac{1}{2}$ inch and the air gap 66g might be about .0015 inch.

The motor 66 is encased at one end by the cap 67. This cap snugly fits over the stator of the motor and defines a fluid seal in conjunction with the gasket 67a. Additionally there is provided an insulating member 67b in the cap 67 and a series of conductor pins 67c embedded therein to permit motor circuit connections without losing the fluid seal of space 67d. The bearing 66h is of a type, such as an unsealed ball bearing, which does not close the passage from the space 67d to the gap 66g of the motor. However the opposite bearing 66j either serves to effect a seal or gasket means (not shown) is provided to prevent the escape of silicone oil from the gap 66g.

The cavity 67d and the gap 66g are flooded with silicone oil. This provides a complete oil film of thin cylindrical conformation between the rotor 66b and the inner periphery of the stator. This inner periphery is of smooth cylindrical conformation and is preferably made in such conformation by flooding the stator, after winding, with a plastic material; allowing the plastic to harden; and then machining the interior surface of the stator to a smooth cylindrical conformation of the requisite diameter.

Since the follow-up or servo system defines a closed circuit amplifying system, it has a natural tendency toward hunting and instability. This is inherent in the system itself. In an apparatus of the kind to which the present invention is applicable the tendency towards hunting and instability is marked. This is in part because of the very considerable inertia of the outwardly extending arms 60 and 62, together with the links 56 and 58 and the pen 54. It is also due to the necessity of providing a large amplification in the amplifier 68, with a comparatively small voltage induced in winding 70a, Figure 3, giving rise to a comparatively great current flow in winding 66c in response to a comparatively small deviation in the position of rotor 70a from the no voltage position. For these reasons the pen 54, Figure 2, has a tendency to form a wavy line and to overshoot or otherwise distort the writing action during rapid writing.

In accordance with the present invention the stability of the system is greatly enhanced by providing a fluid damping effect in the motors 64 and 66. This is accomplished by flooding the motors with a silicone oil, consisting of an oily organo-silicon compound. Such oils are characterized by highly uniform viscosity characteristics over a range of temperatures and by inertness to the plastic material used in the motors. The very minute gap provided between the rotor and stator in the motors serves to provide a very thin film of the oil across which the fluid shearing or viscous action takes place. As a consequence the motors when flooded with the silicone oil serve to generate an increased counter force on the motors

75 as the velocity of shaft rotation increases.

In an actual system it has been found that the viscosity of the silicone oil should be about 500 centistokes for best results. Larger viscosity oils, such as 1000 centistoke oils can be used but tend to make the system sluggish. Oils of lesser viscosity tend to encourage instability and hunt.

It has been found that the damping obtained by the flooding of the receiving motor is highly effective in imparting stability to the follow-up system. This is believed to be due to several effects. One of these is the very high damping constant that can be obtained with the very narrow air gap involved, coupled with the smooth inner and outer surfaces of the rotor and stator of the motors. This results from the fact that the rotor and stator surfaces are very close together, giving only a minute film across which fluid shearing takes place. Additionally, the damping action is at an effective point in the closed cycle control system as it is directly operative on the motors 64 and 66 and is thus effective on the output side of the unit.

Additionally, the mechanism is especially effective because it is unnecessary to provide additional apparatus for damping purposes. The synchro or selsyn, the motor, and the amplifier are all as designed entirely apart from the damping. The damping effect is obtained merely by placing the necessary silicone oil in position to flood the motors 64 and 66. As the motors are sealed in any event, it is a simple matter to flood them with the oil. This is unlike the damping that could be achieved by ordinary means, such as a magnetic brake and eddy current brake, dashpot, or similar apparatus, which not only must be added to the system but inherently increases the inertia—and such increased inertia necessarily makes the system more susceptible to instability and compels the use of a sluggish overall control system.

Because of the highly effective damping provided by the present invention it is not necessary to provide feedback in the amplifier 68. Without the damping such feedback was found necessary to reduce the time delay in the amplifier to a value not giving undue hunting or instability.

While we have shown and described a specific embodiment of the present invention, it will, of course be understood that various modifications and alternative constructions may be made without departing from the true spirit and scope thereof. We therefore intend by the appended claims to cover all such modifications and alternative constructions falling within their true spirit and scope.

What we claim as new and desire to secure by Letters Patent of the United States is:

1. In a drive mechanism for a remote writing instrument having a writing arm driven by a servo system including a motor having a stator member and an armature member with a space therebetween and with one of said members being fixed and the other member being rotatable with respect thereto and being connected to said arm, said system and arm being subject to hunting and flutter which impair the readability of the writing, the improvement comprising: fluid seal means at each end of said members to provide a fluid tight seal between said members at each end of said space; and a liquid dampening medium in said space between said members; whereby the liquid provides a viscous dampening of the movement of the movable member and writing arm to ameliorate the hunting and flutter of the arm.

2. In a drive mechanism for a remote writing instrument having a writing arm driven by a servo system including a motor having a stator member and an armature member with a space therebetween and with one of said members being fixed and the other member being rotatable with respect thereto and being connected to said arm, said system and arm being subject to hunting and flutter which impair the readability of the writing, the improvement comprising: fluid seal means at each end of said members to provide a fluid tight seal between said members at each end of said space; and an oil of relatively uniform viscosity characteristics in said space between said members as a dampening medium; whereby the oil provides a viscous dampening of the movement of the movable member and writing arm to ameliorate the hunting and flutter of the arm.
3. In a drive mechanism for a remote writing instrument having a writing arm driven by a servo system including a motor having a stator member and an armature member with a space therebetween and with one of said members being fixed and the other member being rotatable with respect thereto and being connected to said arm, said system and arm being subject to hunting and flutter which impair the readability of the writing, the improvement comprising: fluid seal means at each end of said members to provide a fluid tight seal between said members at each end of said space; and a silicone oil having a viscosity of about 500 centistokes in said space between said member as a dampening medium; whereby the oil provides a viscous dampening of the movement of the movable member and writing arm to ameliorate the hunting and flutter of the arm.
4. In a drive mechanism for a remote writing instrument having a writing arm driven by a servo system including a motor having a stator member and an armature member with a space therebetween and with one of said members being fixed and the other member being rotatable with respect thereto and being connected to said arm, said system and arm being subject to hunting and flutter which impair the readability of the writing, the improvement comprising: providing a relatively smooth surface on the portions of said members defining said space; said members being so proportioned that the width of said space between the members is very small; fluid seal means at each end of said members to provide a fluid tight seal between said members at each end of said space; and a liquid dampening medium in said space between said members; whereby the liquid provides a viscous dampening of the movement of the movable member and writing arm to ameliorate the hunting and flutter of the arm.
